CLAIM

The ornamental design for a reel hub for magnetic tape,
as shown and described.

DESCRIPTION

FIG. 1 is a perspective view of a reel hub for magnetic
tape showing my new design;

FIG. 2 is a front elevational view thereof, the rear view
appearing the same;

FIG. 3 is a top plan view thereof, the bottom view
appearing the same;

FIG. 4 is a typical side elevational view thereof; and

FIG. 5 is a cross sectional view taken along the line
A—A of FIG. 3.
